DESIGN FOR A COMBINED CASE AND HOLDER FOR A BOTTLE OF PERFUME OR THE LIKE

Félicie Eugénie Amélie Wanpouille Bergaud,
Paris, France

Application January 18, 1940, Serial No. 89,561

Term of patent 7 years

To all whom it may concern:

Be it known that I, Félicie Eugénie Amélie Wanpouille Bergaud, a citizen of the French Republic, residing at Paris, France, have invented a new, original, and ornamental Design for a Combined Case and Holder for a Bottle of Perfume or the like, of which the following is a specification, reference being had to the accompanying drawing, forming part thereof.

bined case and holder for a bottle of perfume or the like, showing my new design; Figure 2 is a rear elevational view thereof; Figure 3 is a side elevational view thereof.

I claim:

The ornamental design for a combined case and holder for a bottle of perfume or the like, substantially as shown.

FÉLICIE EUGÉNIE AMÉLIE
WANPOUILLE BERGAUD.
